UNITED STATES PATENT OFFICE.

ALVIN P. LANDRY, OF LYNN, MASSACHUSETTS.

CURTAIN ROLLER.

Application filed March 21, 1927. Serial No. 176,911.

This invention relates to curtain rollers and has for its object the production of a device of this character by which the curtain may be stopped at any point and in which a weight overbalances the raising mechanism and means is provided to retard the lowering of the curtain by said weight.

This object is attained by the mechanism illustrated in the accompanying drawings.

For the purpose of illustrating the invention, one preferred form thereof is illustrated in the drawings, this form having been found to give satisfactory and reliable results, although it is to be understood that the various instrumentalities of which the invention consists can be variously arranged and organized, and the invention is not limited to the precise arrangement and organization of these instrumentalities as herein shown and described except as required by the scope of the appended claims.

Of the drawings

Figure 1 represents an elevation of a curtain mounted upon a roller embodying the principles of the present invention, the opposite ends of said roller being mounted in suitable supports.

Figure 2 represents an elevation of one end of the roller.

Figure 3 represents a section of same on line 3, 3, on Fig. 2 and showing the retarding device in elevation.

Figure 4 represents an elevation of the support having the retarding mechanism mounted thereon.

Figure 5 represents a section of same on line 5, 5 on Fig. 4.

Figure 6 represents an elevation of the opposite end of the roller.

Figure 7 represents a section of same on line 7, 7 on Fig. 6, and showing the right hand support in elevation.

Figure 8 represents an elevation of the notched support for the right hand end of the roller.

Figure 9 represents a vertical section on line 9, 9 on Fig. 7, and

Figure 10 represents an elevation of disk member to which the outer end of the roller spring is secured.

Similar characters indicate like parts throughout the several figures of the drawings.

In the drawings 10 is a curtain the upper end of which is secured to the roller 11 while

the lower end of the curtain has mounted therein a curtain stick 12.

This stick 12 is preferably weighted to keep the curtain flat and to overbalance the tension of the curtain spring, one means of weighting the stick being by forming openings 13 therein in which weights 14 may be disposed.

The particular means used for weighting the stick 12 forms no part of the present invention.

At one end of the roller 11 and secured to the window frame is a support 15 having a pintle 16 on which is revolubly mounted a ratchet 17 provided at its inner end with a flange 18.

This ratchet 17 is cylindrical with its teeth on the end opposite the end of the roller 11.

The support 15 is also provided with lateral studs or ears 19 having notches 20 near their bases.

A flat spring 21 is provided with projections 22 at its opposite ends, these projections being disposed in said notches 20 with the central portion of said spring bearing against the periphery of ratchet 17 and causing sufficient friction to retard the rotation of the ratchet 17 about its pintle 16.

The tension of the spring 21 retains the projections 22 in the notches 20 and prevents their accidental displacement.

One edge of the spring 21 contacts with the face of the flange 18 and prevents the displacement of the ratchet 17 from the pintle 16.

The pintle 16 has a central socket 23 into which extends a cylindrical projection 24 formed upon a cup-shaped member 25 mounted upon one end of the roller 11 and revoluble therewith.

Extending through an opening in the member 25 is a pawl 26 the beveled end of which engages the teeth of the ratchet 17.

The pawl 26 is retained in engagement with the ratchet 17 by a spring 27 within a cavity in the end of the roller 11.

When the curtain 10 is pulled downwardly the pawl 27 will engage the teeth of the ratchet 17 and cause it to rotate about the pintle 16, the speed of rotation of said ratchet being limited by the spring 21, but when the curtain is moved upwardly the pawl 27 will ride over the teeth of said ratchet and the curtain 10 will be raised.

without moving the ratchet 17 about its axis.

Under normal conditions the weight of the stick 12 is sufficient to prevent the raising of the curtain by means of its raising mechanism.

As the spring 21 is in frictional contact with the ratchet 17 while the curtain is being pulled down, it is obvious that the rotation of the ratchet will be retarded to a certain degree so that the weight of the stick will not move the curtain down too far.

In the opposite end of the roller 11 is a deep socket 28 which is closed at its outer end by a ferrule 29 having disposed therein a disk 30 provided with a central opening or bearing 31 in which is positioned the reduced portion 32 of a rod 33 which is centrally disposed in the socket 28.

A long helical spring 34 surrounds the rod 33 and one end of this spring is secured to the end of the rod 33 while the opposite end of the spring is secured to the disk 30.

The spring 34 is so wound that it is adapted to rotate the roller 11 in a direction to raise the curtain 10.

The outer end of the rod 33 is provided with a flat sided projection 35 adapted to be disposed in a flat sided notch 36 in a fixed support 37 secured in any well known manner to a window frame.

The bearing 31 has a key way or notch 38 extending lengthwise thereof in which a pin 39 is adapted to be disposed when the spring has been wound sufficiently to raise the curtain 10.

When the cylindrical projection 24 has been inserted into the socket 23 the flat sided projection 35 must be inserted into the notch 36 while the roller 11 is held from turning.

This insertion can only be accomplished by forcing the rod 33 inwardly and this inward movement of said rod will remove the pin 39 from the key way 38 so that the spring 34 will be in condition to act when it is desired to raise the curtain 10.

The upper end of the support 37 flares outwardly as at 40 so that when the flat sided projection 35 is being inserted into the notch 36 the shoulder 41 on the rod 33 will engage the face of the support and as it is moved downwardly over the flaring surface the rod 33 will be forced inwardly against the tension of the spring 34.

The friction between the flat spring 21 and the periphery of the ratchet 17 is sufficient to counterbalance the weight of the stick 12.

If the operator grasps the lower end of the curtain 10 and raises the weighted stick, the tension of the spring 34 will then raise the curtain as soon as it is relieved of the weight of said stick, and consequently the roller will be slowly rotated and the curtain raised.

When the operator releases his hold upon the curtain the weight of the stick 12 will be sufficient to retain the curtain at any desired point, the friction on the ratchet 17 counteracting the weight of the stick to such an extent that when the stick is released the curtain will remain at that point.

By this means the curtain may be stopped at any desired point and it is impossible for the spring 34 to cause the roller to race and impart a sudden raising of the curtain beyond the point where it is desired to have it rest.

It is believed that the operation and many advantages of the invention will be fully understood without further description.

Having thus described my invention, I claim—

1. In combination with a curtain roller provided at one end with means for imparting rotation to said roller and raising the curtain and having a weight overbalancing the tension of the raising means, means coacting with the opposite end of the roller for counterbalancing said weight and retarding downward movement of the curtain.

2. In combination with brackets supporting a curtain roller provided at one end with means for imparting rotation thereto and having a pawl extending from the opposite end thereof; a rotatable ratchet with which said pawl coacts mounted upon one of said brackets; and a retarding member coacting with the periphery of said ratchet.

3. In combination with a curtain roller provided at one end with means for imparting rotation thereto and having a pawl extending from the opposite end thereof; a fixed support; a ratchet revolvably mounted upon said support and with which said pawl coacts; and means mounted on said bracket and coacting with the periphery of said ratchet for retarding the rotation of said ratchet when the curtain is being lowered.

4. In combination with a curtain roller provided at one end with means for imparting rotation thereto and having a pawl extending from the opposite end thereof; a fixed support; a ratchet revolvably mounted upon said support and with which said pawl coacts; and frictional means mounted on said bracket and coacting with the periphery of said ratchet for retarding the rotation of said ratchet when the curtain is being lowered.

5. In combination with a curtain roller provided at one end with means for imparting rotation thereto and having a pawl extending from the opposite end thereof; a fixed support; a flanged ratchet revolvably mounted upon said support and with which said pawl coacts; and means mounted on said bracket for retarding the rotation of said ratchet when the curtain is being lowered and coacting with the flange of said

ratchet to retain said ratchet on said support.

6. In combination with a curtain roller provided at one end with means for imparting rotation thereto and having a pawl extending from the opposite end thereof; a fixed support provided with a pintle alined with the axis of said roller; a ratchet revolute upon said pintle and having a flange at its inner end; two studs extending laterally from said support; and a flat spring secured at its ends to said studs with its central portion in frictional engagement with the periphery of said ratchet.

7. In combination with a curtain roller provided at one end with means for imparting rotation thereto and having a pawl extending from the opposite end thereof; a fixed support provided with a pintle alined with the axis of said roller; a ratchet revolute upon said pintle and having a flange at

its inner end; two studs extending laterally from said support and having notches in the peripheries thereof; and a flat spring having extensions at its opposite ends positioned in said notches, the central portion of said spring being in frictional engagement with the periphery of said ratchet with one edge abutting said flange.

8. In combination with a curtain roller provided at one end with means for imparting rotation thereto and having a spring-pressed pawl extending from the opposite end thereof; a ratchet with which said pawl coacts during the lowering of the curtain to impart rotation to said ratchet; and a retarding member coacting with said ratchet.

Signed by me at 746 Old South Bldg., Boston, Mass., this 18th day of March, 1927.

ALVIN P. LANDRY.
